LOG CARRIER

Charles Emil Nordin, Comox, British Columbia,
Canada

Application June 16, 1945, Serial No. 599,864

4 Claims. (Cl. 114—73)

1

My invention relates to improvements in log carriers which are particularly adapted for transporting logs by sea from the logging operations to the saw mills.

The objects of the invention are to provide means whereby the logs may be easily loaded into holds or pockets in the carrier or vessel and released in groups at destination without danger to personnel or equipment; to provide means whereby the discharge of the logs is through the sides of the vessel, so that after loading no logs have to be raised from their stowed position, and to provide means whereby the logs are held immovable relative to the vessel during transit.

The invention contemplates a carrier conforming generally to the contours of a ship and holds formed therein capable of top loading and side discharge and a cable means disposed vertically of the discharge side of each hold for supporting the logs in position during loading, as will be more fully described in the following specification and shown in the accompanying drawings, in which:

Fig. 1 is a side elevational view of the invention.

Fig. 2 is an enlarged transverse sectional view taken on the line 2—2 of Figure 1.

Fig. 3 is a detail sectional view of the cable shaft tightening device.

Fig. 4 is a sectional view of the shaft and cable engaging means.

Fig. 5 is a plan view of a modified means for securing the cables in log supporting position.

Fig. 6 is an elevational view of said modification.

In the drawings like characters of reference indicate corresponding parts in each figure.

The numeral 1 indicates generally the carrier or vessel which consists of a pontoon 2 terminating at its forward end with a prow 3. The pontoon 2 is provided with a deck 4 sloping downwardly from a longitudinal partition 5 which extends to the main deck 6. The vessel is divided transversely into holds 7 by bulkheads 8 and are connected together at their upper outer ends with heavy deck beams 9 which form the vessel's rails and define deck hatches 10 between each beam and the partition 5 and side openings 11 between the beams and the outer edge of the pontoon deck 4. The partition 5 carries a runway 13 and the beams carry runways 14 which form part of the deck and access from one runway to another is across the deck covering the bulkheads, which are of substantial width as the hatches 10 and the side openings 11 are of equal length, so that

2

logs lowered into a hold 7 with one end engaging a bulkhead may roll out of said hold through its opening 11 without fouling any part of the structure.

Secured to the outer edge of the deck 4 of each hold 7 is a plurality of cables 17, each of which is fitted with a turnbuckle 18 intermediate its length, the upper end of said cable is provided with an eye 20, see Figure 4, by which it is secured at its upper end. The means for tightening the cables 17, which is shown in Figures 3 and 4, consists of a horizontal shaft 22 which extends above each of the openings 11. The shaft 22 is journaled in bearings 23 and 24 and is fitted directly over each cable 17 with a small drum or boss 26 which is provided with a hook 27 to engage the eye 20 of the cable 17. The bearing 24 is fitted preferably directly over a bulkhead and encloses a worm gear 29 which is secured to the shaft, said bearing also journals an inclined shaft 30 to which is secured a worm 31 engaging the gear 29 and a collar 32 which is recessed to receive a detachable handle or key 34.

In the modified means for supporting the cable 17 in vertical position, bearings 38 and 39 are provided along the runways 14 and over each side opening 11. In the bearings 38 a rectangular rod 40 is slidably mounted, the rod is provided at one end with a rounded threaded portion 41 which passes through the bearing 39. Rockingly mounted upon the screw threaded portion 41 is a hand lever 44 having a reversible pawl 45 of any appropriate type which engages a ratchet 46 formed upon a nut 47 surrounding the screw 41. At suitable distances along the length of the openings 11 slotted brackets 49 are secured to the face of the beam 9 and secured to the rod 40 is a keeper 50 to coact with each bracket 49. Each keeper is provided with an opening 51 extending diagonally inwards from its outer face, one side wall, indicated by the numeral 52, serves to engage a thimble 53 secured to the upper end of the cable 17 to hold it in locked position as shown in Figures 5 and 6, and the opposite side, indicated by the numeral 55 is inclined to act as a wedge to drive the thimble 53 forwardly off the bracket 49 and release the upper end of the cable when the nut 47 is rotated in appropriate direction by means of the lever 44. Secured to the partition 5 or to the pontoon deck 4 is a plurality of flexible members 57 which are adapted to pass around all the logs lowered into a hold 7 and be clamped, after suitable tightening, to appropriate fastening devices 58 mounted upon the runways 13.

In operation, the cables 17 are secured in ver-

tical position. Where the tightening means shown in Figures 3 and 4 are used, the eye 20 of each cable 17 will be placed upon its hook 27 and the shaft 22 rotated by means of the key 34 to tighten up all the cables simultaneously. It is intended that the tightening should be done with say from a quarter to a half turn of the shaft, therefore if there is any appreciable difference in the length of the cables in front of any side opening 11 they may be brought to uniformity by the turnbuckles 18. When the cables 17 are securely held in vertical position as shown on the right hand side of Figure 2, the flexible members 57 are brought up inside of and over its beam 9, then logs are loaded into the hold 7 through the hatch 10, and the side thrust of the logs will be countered by the vertical cables 17 which may be reinforced by having a vertical timber 60 erected alongside each cable and lashed thereto, such timber being obviously interposed between the cable and the log load. The interposition of these timbers will maintain the alignment of the side of the log load of each pocket substantially with the side of the vessel, thus reducing drag in towing. When the load is in place, the free ends of the flexible members 57 are brought over to the runway 13 and are tightened up by appropriate means and made fast to the devices 58.

On reaching destination logs are discharged from any hold through the opening 11, by first releasing the members 57 then turning the shaft 22 until the hooks 27, which are aligned, simultaneously drop their cables 17 and allow the logs to run out and be launched into the water.

Where fastening devices as shown in Figures 5 and 6 are used, the thimbles 53 of the cables 17 are placed in position upon the brackets 49 and the rod 48 is moved endwise to dispose the side 52 of the opening 51 of the keepers 50 in front of the thimbles as shown, then the turnbuckles 18 are tightened up to the proper tension and the holds 7 loaded and secured as above mentioned. In releasing the log load, after the flexible members 57 are unfastened, the lever 44 is actuated to move the rod to the left, as viewed in Figures 5 and 6, when the wedge sides 55 of the keepers 50 thrust against their respective thimbles 53 to urge them outwardly from the brackets 49 and allow the cables 17 to fall away from the top and the log load to discharge into the water.

It will be obvious that with the cables 17, with or without the load aligning timbers 60 forming the closure of the outer side of each hold 7, that said closure will necessarily be much lighter and more convenient to handle than the heavy gate structure heretofore proposed and also that this structure being both light and flexible is not subject to damage of any kind when the log load is released.

It will be obvious that the shafts and other equipment controlling the release of the cables 17 will be suitably guarded against damage when loading the vessel.

What I claim as my invention is:

1. A log carrier comprising a pontoon having sides and a central partition, a deck sloping downwardly from said partition to the sides of said pontoon, bulkheads extending transversely of said pontoon to divide the deck into a plurality

of holds, a beam extending lengthwise above each side of the pontoon defining a hatch and a side opening for each of the holds, spaced vertical cables adapted to be tensioned between the side 5 of the pontoon and a beam for forming a closure for one of the side openings, and means for simultaneously releasing one end of each of said cables.

2. A log carrier comprising a pontoon having 10 sides and a central partition, a deck sloping downwardly from said partition to the sides of said pontoon, bulkheads extending transversely of said pontoon to divide the deck into a plurality of holds, a beam extending lengthwise above 15 each side of the pontoon defining a hatch and a side opening for each of the holds, spaced vertical cables adapted to be tensioned between the side of the pontoon and a beam for forming a closure for one of the side openings, and means for simultaneously releasing one end of each of 20 said cables, and a rigid elongated member secured to some of the cables between their extremities.

3. A log carrier comprising a pontoon having 25 sides and a central partition, a deck sloping downwardly from said partition to the sides of said pontoon, bulkheads extending transversely of said pontoon to divide the deck into a plurality of holds, a beam extending lengthwise above 30 each side of the pontoon defining a hatch and a side opening for each of the holds, spaced vertical cables adapted to be tensioned between the side of the pontoon and a beam for forming a closure for one of the side openings and means 35 for simultaneously releasing one end of each of said cables, said releasing means comprising a shaft mounted parallel to one end of each of said cables, said shaft having aligned devices each adapted to releasably engage an end of a cable, 40 and means for turning the shaft to release the engaging means from the cable ends.

4. A log carrier comprising a pontoon having 45 sides and a central partition, a deck sloping downwardly from said partition to the sides of said pontoon, bulkheads extending transversely of said pontoon to divide the deck into a plurality of holds, a beam extending lengthwise above 50 each side of the pontoon defining a hatch and a side opening for each of the holds, spaced vertical cables adapted to be tensioned between the side of the pontoon and a beam for forming a closure for one of the side openings, and means 55 for simultaneously releasing one end of each of said cables, said releasing means comprising a shaft mounted parallel to one end of each of said cables, said shaft having aligned devices each adapted to releasably engage an end of a cable, a worm and worm wheel drive for rotating the shaft to alternatively tension the cables across 60 the opening and to release the engaged ends of said cables.
